UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

IRONING-MACHINE.

1,351,031.

Specification of Letters Patent. Patented Aug. 31, 1920.

Application filed October 23, 1916. Serial No. 127,246.

To all whom it may concern:

Be it known that I, ALVA J. FISHER, a citizen of the United States, residing at Evanston, in the county of Cook and State 5 of Illinois, have invented certain new and useful Improvements in Ironing-Machines, of which the following is a specification.

My invention relates to ironing machines of that type in which a heated shoe operates with a padded roll in the ironing 10 operation, and pertains more particularly to the construction and operation of the shoe. The general object of my invention is to provide such a construction of pivoted 15 shoe so that the same can be swung away from the roll in the regular or normal operation of the machine, and can also be moved bodily away from the roll to an abnormal position whenever it is desired to 20 clean or dress the inner or operating surface of the shoe. To this end I provide novel operating connections for normally holding the shoe against the roll with a yielding pressure and for supporting it 25 when swung away from the roll, and I provide in addition a construction whereby the entire pivotal mounting of the shoe can be moved bodily away from the roll so as to remove the shoe a considerable distance 30 from the roll for the special purpose explained.

In the drawings Figure 1 is a side elevation of my machine; Fig. 2 an end view thereof; Fig. 3 a cross-section on the line 35 3—3 of Fig. 1, but on a larger scale and showing in full lines the shoe in coöperative position with respect to the roll and in dotted lines in its ordinary swung-away position; Fig. 4 a view similar to Fig. 3 excepting that the shoe has been moved away 40 from the roll to its abnormal position; Fig. 5 a sectional elevation of the yielding connection acting on the shoe to hold it in position against the roll; and Fig. 6 a plan view of the lefthand end of this connection 45 as shown in Fig. 5.

Inasmuch as my invention pertains only to the shoe of the ironing machine only those parts of such machine as are directly 50 concerned need be explained. The machine frame 1 has at its opposite ends brackets or end frames 2 in which the roll 3 is journaled. The shoe 4 is provided as usual with the heating chamber 4^a and with the curved 55 ironing face 4^b which is adapted to press

against the roll 3. The shoe is provided at opposite ends with depending portions or arms 5 carrying at their lower ends horizontal pivots 6, which extend on opposite sides of such arms, the outer ends of such 60 pivots being received within oblique slots 2^a in the end frames of the machine, said slots sloping upwardly away from the vertical plane through the roll so that the rear faces of the slots, coacting with the pivots 65 for the shoe, resist effort to displace the shoe bodily in a rearward direction, and define the normal position of the shoe's pivotal axis.

The yielding operating connections which 70 coöperate with the shoe are arranged in two sets one at each end of the shoe. As the sets are similar in construction a description of one will apply to both. At the front side of the machine a rock shaft 7 is supported in the end frames 2 of the machine and provided with an operating handle 8. At each end this rock shaft has secured to 75 it a pair of arms 9 between whose outer ends and the shoe is interposed the yielding operating connection. As shown in detail in Fig. 5 this yielding connection consists of 80 two heads 10 and 11, adapted to telescope on each other and kept apart by means of the coiled spring 12. The outermost head 85 10 is pivotally mounted upon the outer end of the arms 9 and is provided with a central bore 10^a adapted to receive the rod or stem 13, which is secured to the other head 11. The spring 12 bears at one end against the 90 head 11 and at the other end against the adjusting nut 14, screwing onto the head 10, whereby the tension of the spring may be 95 adjusted. The outer end 11^a of the head 11 is ball-shaped and is adapted to be received by a socket 5^a in the shoe. When the rock shaft 7 is rocked in anti-clockwise direction, Fig. 3, and to the dotted line position shown in that figure, the pressure of the operating connections against the shoe will be relieved 100 and such shoe will drop away slightly from the roll by virtue of its gravity, the pivotal movement being on the pivots 6 as the axis of movement, it being understood that during this movement these pivots remain in fixed 105 position at the lowermost ends of the slots 2^a. When the rock shaft is restored to normal position the pivotal point 9^a takes a position below the line between the center of the rock shaft 7 and the point of contact of 110

the ball-shaped end of the head 11, so that the operating connections bearing against the shoe are locked in position.

The above described construction provides for ordinary operating movements of the shoe, but in order that the shoe may be bodily swung away from the roll at a considerable distance, I provide means for bodily moving the pivot 6 upwardly in the slots 2^a upon an abnormal movement of the rock shaft 7. These means consist of the links 15, the outer ends of which are pivotally connected to the pivot 9^a and the inner ends of which are slotted at 15^a to receive the pivot 6. In the normal operation of the connections described these links have no function inasmuch as by virtue of the slots 15^a the links merely slide upon the pivots, but upon an abnormal movement of the rock shaft the ends of the slots will engage the pivots 6 and move them upwardly in the oblique slots 2^a, so that the shoe which by the preliminary or normal movement of the operating connections has been swung away from the roll on the pivot 6 will be bodily moved away from the roll to the position shown in Fig. 4, which gives the proper amount of access to the ironing face of the shoe for the purpose of cleaning and dressing the same.

I claim:

1. In an ironing machine, the combination of a roll, a coacting shoe, mountings for said shoe permitting the shoe to turn into and out of contact with the roll in normal operation about a pivotal axis that is beyond the roll-contacting surface of the shoe and permitting the rearward displacement of said shoe bodily from said normal-operation-position, and means for controlling the rocking of the shoe pivotally and for bodily displacing it as aforesaid.

2. In an ironing machine, the combination of a roll, a shoe coöperating therewith, bodily displaceable pivots for said shoe beyond the roll-contacting surface thereof, whereon said shoe may swing into and out of contact with the roll in normal operation, and operating means connected and movable to first occasion a rocking of the shoe on its pivots out of roll-contacting position and thereafter bodily to displace its pivots and further separate the roll and shoe.

3. In an ironing machine, the combination of a roll, a shoe coöperating therewith having horizontal pivots beyond the contact-arc of the shoe whereon said shoe may be swung into and out of contact with the roll, means normally positioning said pivots for said coaction of the roll and shoe and permitting bodily displacement of the pivots backwardly from and vertically with respect to the roll, and operating means connected and movable to occasion a rocking

of the shoe on its pivots out of roll-contacting position and thereafter to bodily displace its pivots.

4. In an ironing machine, the combination of a roll, a shoe for coöperation therewith having pivots beyond the contact-arc of the shoe whereon the shoe may be swung into and out of contact with the roll, a structure wherein said pivots are mounted for displacement thereof to separate the shoe relatively widely from the roll, and operating means comprising a part for controlling the rocking of the shoe pivotally without pivot displacement and another part for displacing the shoe pivots.

5. In an ironing machine, the combination of a roll, a shoe coöperating therewith, a pivot on which the shoe is mounted to swing toward and away from the roll, a swinging arm, a yielding connection between the arm and shoe, and a link coöperating with the swinging arm and pivot, said link having a slot to accommodate normal movements of the arm but adapted to engage and move the pivot bodily laterally when the swinging arm and link are moved an abnormal distance.

6. In an ironing machine, the combination of a roll, a shoe coöperating therewith, a pivot on which the shoe is mounted to swing toward and away from the roll, a rock shaft, an arm secured thereto, a yielding connection between the arm and shoe, a link pivoted at one end to the arm and having at the other end a closed slot through which said pivot passes, said slot accommodating normal movements of the arm but in an abnormal movement thereof the end of the slot being adapted to engage and move the pivot bodily laterally.

7. In an ironing machine, the combination of a roll, a shoe for coöperating therewith, pivots for said shoe beyond its contact-arc and whereon the shoe may be swung into and out of contact with the roll, a structure wherein said pivots are mounted for displacement thereof to separate the shoe relatively widely from the roll, normally to position the shoe to be swung into and out of contact with the roll, and operating connections for said shoe comprising a movable member controlling the pivotal action of the shoe and arranged to support said shoe when swung away from the roll, and another member controlling the displacement of the shoe pivots.

8. In an ironing machine, the combination of a roll, a shoe coöperating therewith, a pivot on which the shoe is mounted to swing toward and away from the roll, said shoe having a depending portion to which the pivot is secured, a frame for the roll provided with a slot in which the pivot is bodily movable, a yielding movable member for normally holding the shoe against

the roll when in operation and supporting such shoe when swung away from the roll, and an operating connection between said member and the pivot for engaging and 5 moving the pivot bodily in said slot upon an abnormal movement of said member.

9. In an ironing machine, the combination of a roll, a shoe coöperating therewith, a pivot on which the shoe is mounted to swing 10 toward and away from the roll, a rock shaft, yielding operating connections between such shaft and the opposite ends of the shoe for normally holding the shoe pressed against the roll, and connections between such operating 15 connections and the shoe pivot for moving the pivot bodily upon abnormal movement of the rock shaft.

10. In an ironing machine, the combination of a roll, a shoe coöperating therewith, a pivot on which the shoe is mounted to swing 20 toward and away from the roll, a rock shaft, yielding operating connections between such shaft and the opposite ends of the shoe for normally holding the shoe pressed against 25 the roll, and links between such operating connections and the shoe pivot, said links being slotted at one end to accommodate the pivot.

11. In an ironing machine, the combination of a roll, a shoe coöperating therewith, and means for holding the shoe pressed against the roll, including two heads telescoping with each other one of which bears 30 against the lower portion of the shoe but is 35 unconnected therewith, and a spring for holding the heads apart.

12. In an ironing machine, the combination of a roll, a shoe coöperating therewith having pivots beyond the contact-arc of the 40 shoe whereon the shoe may be swung into

and out of contact with the roll, a structure wherein said pivots are mounted for displacement of the shoe relatively widely from the roll, and operating means comprising a handle, a toggle lever interposed between 45 said handle and shoe and having a telescopic spring-pressed member with means for adjusting the spring tension, and lost-motion connections between the pivots and handle for displacing the shoe pivots bodily upon 50 abnormal movement of the handle.

13. In an ironing machine, the combination of a roll, a shoe coöperating therewith, and means for holding the shoe pressed against the roll, including two heads telescoping with each other, a spring for holding the heads apart, one of the heads being ball-shaped at its end, and the shoe having 55 a socket for such ball end.

14. In an ironing machine, the combination of a roll, a shoe coöperating therewith, and means for holding the shoe pressed against the roll, including a rock shaft, an arm secured thereto, two heads telescoping with each other, one of which is pivotally 60 mounted onto the arm and the other of which bears against but is unconnected with the shoe, and a spring between said heads to keep them distended.

15. In an ironing machine, the combination of a roll, a shoe coöperating therewith, and means for holding the shoe pressed against the roll, including a rock shaft, an arm secured thereto, two heads movable toward and away from each other, a spring 70 for holding the heads apart, one head being pivotally mounted on the arm and the other having a ball-shaped end, the shoe having a socket to receive such ball end.

ALVA J. FISHER.
